UNITED STATES PATENT OFFICE.

SETH CURLIN, OF COVINGTON, TENNESSEE, ASSIGNOR TO THE CURLIN SWITCH AND CROSSING COMPANY, OF KENTUCKY.

AUTOMATIC SWITCH-SIGNAL.

SPECIFICATION forming part of Letters Patent No. 331,870, dated December 8, 1885.

Application filed November 13, 1884. Serial No. 147,870. (No model.)

To all whom it may concern:

Be it known that I, SETH CURLIN, a citizen of the United States, residing at Covington, in the county of Tipton and State of Tennessee, 5 have invented certain new and useful Improvements in Automatic Switch-Signals; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to railroad-switches 15 and their signals; and the novelty consists in the construction, arrangement, and adaptation of the several parts for automatic action, as will be more fully hereinafter set forth, and specifically pointed out in the claims.

20 The essential object of my invention is to produce, in connection with a switch which is operated automatically by a passing train to open the main track, a signal which, by the action of the movable switch-rails which form a part of the side track when the switch is thrown to complete connection between the main track and siding, will automatically display a danger-signal, and which will take in and conceal such danger-signal when the switch 30 is open by the passing train or otherwise.

To the simplicity, efficiency, and comparatively inexpensive manufacture of my peculiar mechanisms I attach importance.

For convenience I will illustrate and describe the invention as applied to a single track and siding; but it will be obvious that the construction would be equally advantageous and valuable in other relations.

The accompanying drawings fully illustrate 40 the essential features of the invention, and form a part of this specification.

Referring thereto, Figure 1 is a plan view showing the switch closed and the siding in connection with the main track. Fig. 1^a is a side elevation of the signal apparatus and its connections, with the switch-rails corresponding to Fig. 1, and showing the several rails in transverse section, the danger-signal being exposed. Fig. 2 is a plan view corresponding 50 to Fig. 1, but showing the switch and main

track open. Fig. 2^a is an elevation of the apparatus corresponding to Fig. 1^a, but showing the danger-signal concealed, to denote the condition of the switch shown in Fig. 2; and Fig. 3 is an enlarged elevation of the signal and stand, taken at right angles to the position shown by the same parts in Figs. 1^a and 2^a.

Referring to the drawings, A and A' designate the rails of the main track, B and B' the rails of the siding, and C and C' the movable switch-rails, pivoted at c to the ends of the rails B B', respectively. The switch-rails C C' are rigidly secured to a cross-bar, D, so that they shall at all times occupy correct relative positions with each other, and the cross-bar 65 D is connected, as hereinafter described, to a crank, e, upon a rock-bar, E, journaled in proper boxes, e', along the main track. This rock-bar E may be turned in either direction, to open or close the switch, by any suitable 70 means. I have shown a lever, E', for that purpose.

The switch will be opened—that is to say, thrown out of contact with the main track—by a passing train. To illustrate the point, let 75 it be supposed that trains going in opposite directions are to pass this point. The switch is first thrown to connect the siding with the main track, as seen in Fig. 1, and the train coming toward the left passes upon the siding and 80 halts or “slows” until the train coming toward the right passes, and the flanges of the wheels striking the switch-rail C will automatically open the switch, and the said train passes along the main track without interruption, it being 85 only necessary to slow sufficiently to allow the switch to be operated without damage.

By the construction of the switch I avoid the necessity of cutting, weakening, or in any way altering the form of the main rails, the 90 switch-rails having peculiarities of form which are made the subject of a separate application.

Under the condition described the necessity of infallible signaling will be apparent. A train coming toward the left must be signaled 95 that the switch is closed or set for siding and the siding occupied, and a train coming to the right must be signaled that the switch is closed or set for siding, and it must pass the point slowly, in order to open the switch without too

straining or destroying the parts. When the switch is open, the main track is perfect, and no necessity for care exists. My invention is designed to secure this infallible system of 5 signaling.

An arm, G, is secured to the bar D at one end, and has its opposite end pivoted to a link, G', which in turn is loosely pivoted to a bell-crank lever, H, pivoted at *h* to a hollow stand- 10 ard, M', braced as seen at M', and secured to a base, O, which may be one of the cross-ties. To the other arm of this elbow-lever H is pivoted a link, I, and the upper end of this link, at *i*, is pivoted to a sheet-metal danger-signal, 15 J, pivoted at *k* between two plates, K, of corresponding shape and size. This danger-signal J is preferably painted red and the plates K white, and their relation to each other is such that when the apparatus is at rest and 20 the switch opened or broken (the main track clear) the signal J is concealed in either direction by the plates K. The pivot K is also away from the center, so that the heavier end is away from the track, and the normal position is when the main track is clear, as seen 25 at Fig. 2^a. The plates K are supported by a shank, M, which fits in a socket in the post M', and is adjustable to take up slack and keep a proper relation of parts by a set-screw, *n*, 30 as shown in Fig. 3.

The operation of the invention is obvious. When the switch is thrown into connection with the main track and the siding is closed, the act which makes that condition automatically sets the danger-signal, and when a passing train again opens the main track the same forces serve to take in and conceal the danger-signal and to declare that the track is clear. 35

Without confining myself to the exact form and proportion of parts herein shown and described, what I claim as new is—

1. The combination, with the rails A A' B B' and switch-rails C C', of the bar D, secured to said rails C C', means for moving said bar to close the switch, the signal J, the plates K, 45 the link I, elbow-lever H, and links G G', as and for the purpose set forth.

2. The combination, with the post M', having socket, two plates, K, having shank M, signal J, and its connections with the switch, 50 of the set-screw *n*, as and for the purpose set forth.

In testimony whereof I affix my signature in presence of two witnesses.

SETH CURLIN.
